UNITED STATES PATENT OFFICE.

ALEX H. SIMON, OF KYLE, TEXAS.

DISPLAY-CASE.

No. 926,298.

Specification of Letters Patent.

Patented June 29, 1909.

Application filed August 28, 1908. Serial No. 450,735.

To all whom it may concern:

Be it known that I, ALEX H. SIMON, a citizen of the United States, residing at Kyle, in the county of Hays and State of Texas, have 5 invented a new and useful Display-Case, of which the following is a specification.

This invention relates to display cases for holding cheeses whether or not the same are mounted upon cheese cutters, and the object 10 of the invention is to provide a case which can be readily placed over the cheese and which is provided with a movably mounted door and top having means combined therewith whereby motion will be transmitted 15 from the door to the top so that both will open and close simultaneously, thus permitting access to be readily had to the contents of the case.

Another object is to provide a case the top 20 of which can be opened independently of the door.

With these and other objects in view the invention consists of certain novel features of construction and combinations of parts 25 which will be hereinafter more fully described and pointed out in the claims.

In the accompanying drawings is shown the preferred form of the invention.

In said drawings: Figure 1 is a perspective 30 view of the case embodying the present improvements, said case being shown partly open. Fig. 2 is a vertical longitudinal section through the case, the same being shown closed.

35 Referring to the figures by characters of reference, 1 designates the base frame of the case, the same having side panels 2 and an end panel 3 secured thereto, said panels extending upwardly from the base frame and 40 being fixedly connected and each of them being preferably provided with a glass 4 so that the contents of the case can be viewed at all times. A cross strip 5 is secured upon the upper edge of the end panel 3 and

45 hingedly connected to it is the top panel 6 of the case, said panel consisting of a frame 7 having a screen 8 secured to it, said screen being preferably supported longitudinally by a cleat 9 arranged within the frame 6. The 50 top panel is designed to normally rest by gravity upon the side panels 2 of the case and has substantially V-shaped hangers 10 secured to the sides thereof near the hinges and provided with offset eyes 11. These hangers 55 are arranged close to and between the side panels and the eye of each hanger has a chain

12 or other flexible device connected to it and extending upwardly over a supporting spool or pulley 13 mounted upon the inner face of the side panel adjacent the upper edge 60 thereof. The other ends of the chains 12 are attached to the inner surface of a door 14 hingedly connected at its lower edge to the frame 1 between the side panels 2 and designed to swing upwardly against the side 65 panels when closed.

The door has a suitable handle 15 fastened to it so that it can be readily manipulated; and the chains 12 are so proportioned that when the door 14 is swung downward the 70 chains will pull upwardly on the lower ends of hangers 10 and thus cause the top panel 6 to swing upwardly. Obviously when the door 14 is closed the top panel 6 will swing downward by gravity and become seated 75 upon the side panels 2. It will be understood that whenever the case is to be used for the purpose of protecting a cheese from insects the same can be placed over the cheese and the device on which it is mounted 80 and the screen 8 serves not only to keep insects away from the cheese but also serves to keep the interior of the case thoroughly ventilated. As heretofore stated by swinging the door 14 downward the top panel will be 85 elevated and a portion removed through the large opening thus produced. Obviously when the door 14 is closed the top panel 6 can be swung upwardly without causing the 90 door to swing downwardly because of the flexible connection between the two. The device is very simple, durable, and efficient and can be made in various sizes so as to house cheeses of different sizes and cutters 95 or other devices on which they may be mounted.

What is claimed is:

1. A casing having an opening at the top, bottom and one end, a closure hingedly connected to the end of the casing, a hinged closure for the top of said casing, a hanger fixed with relation to said top closure and extending into the casing, and means secured at its opposite ends to the hanger and to the 105 closure respectively and operated by the opening of the end closure for actuating the hanger and opening the top closure.

2. The combination with a case open at the top, bottom, and one end; of a top panel 110 hingedly connected to the case, a hanger depending therefrom, an end closure hingedly

connected to the case, a flexible connection between the end closure and hanger, and a guide for said connection.

3. The combination with a case open at the top, bottom, and one end; of a top panel hingedly mounted upon the case, a hanger depending therefrom, an end closure hingedly mounted upon the case, a flexible connection between said closure and the hanger and

a guide wheel mounted within the case and 10 supporting the connection.

In testimony that I claim the foregoing as my own, I have hereto affixed my signature in the presence of two witnesses.

ALEX H. SIMON.
